UNITED STATES PATENT OFFICE.

HORACE F. GRUMAN, OF JACKSON, MICHIGAN, ASSIGNOR, BY MESNE ASSIGNMENTS,
TO ARBETTER FELLING MACHINE CO., A CORPORATION OF MAINE.

EDGE-TRIMMING MACHINE.

Application filed March 18, 1921. Serial No. 453,456.

To all whom it may concern:

Be it known that I, HORACE F. GRUMAN, a citizen of the United States of America, residing at Jackson, in the county of Jackson, and State of Michigan, have invented certain new and useful Improvements in Edge-Trimming Machines, of which the following is a specification, reference being had therein to the accompanying drawings.

10 In the art of ornamenting cloth and other materials, such as in embroidery, tapestry, lace making, etc., and particularly in forming an edge finish, it has been the practice to form such edge finish within the body of the material and then cut away by hand, the material lying outside of this edge finish. This is a slow operation and great care is necessary in cutting away the material that the threads forming the edge 15 stitching or embroidery be not severed and that all of the material outside of the edge stitching be cut away.

The object of this invention is to provide suitable means for doing the work of cutting away the material outside of the embroidered or stitched edge, which means may be formed to operate automatically and rapidly without danger of injury to the embroidery and so that no portion of the material will be left to present an unsightly appearance.

A further object is to provide means whereby an irregular outline or edge finish will be automatically followed and the material cut away accurately and closely to such outline. It is also an object of the invention to provide a machine for the purpose which is simple in construction and which may be operated by unskilled labor.

40 With the above and other ends in view, the invention consists in the matters hereinafter set forth and more particularly pointed out in the appended claims, reference being had to the accompanying drawings, in which:

Figure 1 is a vertical section through a machine illustrative of the invention;

Fig. 2 is a detail view of a portion of the machine illustrative of the operation 45 thereof;

Fig. 3 is a detail view of a portion of a cutter and co-operating table;

Fig. 4 is a plan view of the machine shown in Fig. 1 with parts thereof in section;

Fig. 5 is a front end elevation of Fig. 1; and

Fig. 6 is a detail further illustrating the operation of the machine.

In making embroidery or other decorative work applied to various fabrics, it is common practice to form a suitable edge finish which is usually formed by working the edge design into the body of the fabric and then cutting away the edge of the material which lies outside of this edge design. This edge finish may be of irregular shape and the manner of forming the same, the materials used or the kind of stitching employed may vary, but in such instances the applied embroidery or stitching forms a thickened portion by reason of the application of the stitches to the fabric which stitches are usually close together, to provide a firm finished edge for the finished article.

After the embroidery or other edge stitching has been applied to the material, it is necessary to cut away the material outside this edge finish and great care is necessary in doing this in order to prevent injury to the embroidery stitching and at the same time remove all of the body of the fabric outside of the edge finish, and this is particularly true where this edge is irregular in form, as for instance in the form of scallops. A piece of such embroidery is illustrated in the drawings, wherein the body of the material is indicated by the letter A, the edge finish or embroidery at B and the portion of the fabric outside of the edge finish which is to be cut away is indicated at C.

The machine for cutting away the edge of the fabric comprises a suitable casing 1 to the forward side of which is secured a table 2 in any suitable manner, as by a bracket 3, and mounted in suitable bearings 4 in the casing is a shaft 5 upon which is secured a rotary cutter 6, said cutter being positioned opposite a slot 7 in the front wall 100

of the casing to project therethrough. This cutter is formed with peripheral teeth 8, the side walls 9 of each of which converge outwardly to form a comparatively sharp point 10 with a forward face 11 extending transversely of the cutter and its plane of rotation, and inwardly toward the hub or body portion of the cutter. This front face 11 of each tooth is therefore substantially V-shape in plan view and the outer edges of this face form the two cutting edges of the tooth. The inner end of this face 11 meets the inner end of the back face 12 of the next adjacent tooth in the direction of rotation, and thus a series of projecting teeth are formed having forward faces which are substantially triangular or V-form and provide cutting edges which converge outwardly toward the point of the tooth. This forward face 11 of each tooth lies in a plane tangent to a circle, the axis of which is co-incident with the axis of the cutter shaft, that is, this face extends inwardly from the point of the tooth 25 in a plane inclined to a radial plane of the cutter.

The table 2 is provided with a V-shaped notch 13 to receive the cutter teeth, said notch being formed to conform to the shape 30 of the teeth so that as the cutter rotates, the cutting edges of its teeth will pass into close proximity with a cutting upper edge 14 formed on the table along the edge of the notch 13. The wall of the notch below its 35 cutting edge is preferably undercut slightly, as indicated at 15, to provide clearance for the teeth of the cutter and the body of the cutter adjacent the base of the teeth is formed, as shown at 16, with inclined sides 40 conforming to the inclined side faces 9 of the teeth to engage the notch and prevent the cutter from being adjusted relative to the table to a position where the teeth will strike the cutting edge 14 of the table and 45 cause injury to said edge and to the cutting edges of the teeth. The table 2 may be adjustably secured to the bracket 3 by any suitable means, such as screws 17, indicated in dotted lines in Fig. 1.

To hold the fabric body A of the material to be operated upon, down upon the upper face of the table 2, a suitable presser foot 18 is provided. This foot is also formed with a V-notch 19 to receive the teeth of the cutter and upon the lower face of the foot along this V-notch is formed a downwardly extending flange 20 which is preferably thin and has a comparatively sharp lower edge. This lower edge of the flange 20 extends parallel with and directly above the cutting edge 14 of the table 2 and the foot is so supported above the face of the table that a very narrow space is provided between said cutting edge and lower edge of the

flange, said space being just sufficient to permit the fabric edge portion C to pass therethrough. The flange however forms an abutment to prevent the embroidered and therefore thickened portion B from passing into the path of the teeth of the cutter between the lower edge of the flange and the table.

The foot 18 is carried upon the lower end of a shaft 21 which is mounted in a socket member 22 secured to the machine casing 75 and within this socket is a spring 23 sleeved upon the shaft between the lower end of the bore of the socket and a head or flange 24 on the shaft. An adjusting plug 25 is secured into the upper end of the bore of the socket 22 to engage the upper end of the shaft and adjust the same longitudinally against the action of the coiled spring. A lock nut 26 on the plug is provided for locking the plug in position and by means of 85 the adjustment thus provided, the foot 18 may be very accurately positioned relative to the face of the table so that the slot or space between the lower edge of the flange 20 and the cutting edge 14 of the table will 90 be just sufficient to allow for the thickness of the body of the material being operated upon to pass therethrough, the flange engaging thickened portions, such as where embroidery or other stitching is applied 95 thereto, to prevent such stitching from passing into the path of the cutter teeth.

The shaft 5 and cutter may be rotated in any suitable manner, as by means of a pulley 27 on the shaft engaged by a flexible driving belt 28, said pulley and belt being enclosed within a protecting shield 29 secured to the end of the casing 1.

In operation, the foot 18 is first adjusted so that the flange 20 thereon will be spaced from the edge 14 of the table just a sufficient distance to allow the thickness of material to be cut away from the body of the fabric, to pass therethrough. The cutter being in rapid rotation, its teeth engage the portion 105 of fabric which projects beneath the flange 20 and across the V-notch in the table and foot and rapidly cuts it away. The operator moves the body of material across the table, at the same time holding it so that 110 the edge portion which is to be cut away will be forced beneath the flange 20 and so that the thickened portion or embroidered edge finish B will engage this flange at the point of the V-notch, the strip or body of 115 fabric yielding sufficiently to allow the body to move in and out maintaining the uneven or scalloped line of the edge finish in contact with the point of the flange, and thus causing the fabric outside said edge finish 120 to be cut away by the cutting points of the teeth of the rapidly rotating cutter, along and close to this uneven line of stitching 125

All of the fabric body outside of the embroidery close up to the stitching will therefore be cut away without injury to the stitching as the flange 20 prevents the stitching from passing into the path of the cutter teeth, and at the same time, because of the thinness of said flange, permits the stitching to closely approach the cutter. The flange therefore protects the threads or 5 stitching of the embroidery from being cut or injured and at the same time from an abutment, in contact with which the embroidered edge finish is maintained, throughout its entire irregular length. Be- 10 cause of the inclination of the forward face 11 of each tooth of the cutter to a plane passing through the axis of the cutter, each tooth has a shearing action as it passes the longitudinally disposed cutting edge 14 of 15 the table, and thus the threads of the fabric are severed as by a pair of shears and all pulling or wrinkling of the fabric due to 20 drawn threads is prevented.

The machine is very rapid in its opera- 25 tion as the edge of the fabric will be cut away by the rapidly rotating cutter as fast as it is drawn across the table by the operator, and an unskilled person may feed the work to the machine as it is only necessary 30 to hold the body of material in place beneath the foot 18 and move it along, the yielding action of the body of material serving to cause the line of embroidery or 35 edge finish to maintain its contact with the stop flange 20 regardless of the irregular outline of this edge.

Obviously changes may be made in the details of construction and arrangement of parts within the scope of the appended 40 claims without departing from the spirit of the invention and I do not therefore limit myself to the construction shown.

Having thus fully described my invention, what I claim is:—

45 1. In an embroidery edge trimming machine, the combination of a rotary cutter operable about a horizontal axis and having a plurality of peripheral V-shaped teeth, the body of the cutter being formed with inclined sides in alignment with the sides of the teeth, and a horizontal stationary cutting blade having a V-shaped notch to receive the cutting teeth and the inclined sides of the cutter, said inclined sides of the cutter cooperating with the walls of the notch of the blade to retain said cutter and blade in definite cutting relation.

60 2. In an embroidery edge trimming machine, the combination of a rotary cutter operable about a horizontal axis and having a plurality of peripheral V-shaped teeth, each tooth being formed with a cutting edge inclined to a radial plane of the cutter, the inner portion of each cutting tooth being in

advance in the direction of rotation of the 65 outer end portion thereof, the body of the cutter being formed with inclined sides in alignment with the sides of the teeth, and a horizontal stationary cutting blade having a V-shaped notch to receive the cutting teeth 70 and the inclined sides of the cutter, the cutting blade cooperating with the teeth of the cutter to produce a shearing action beginning at the inner end of each tooth and the inclined sides of the cutter cooperating with 75 the walls of the notch of said blade to retain the cutter and blade in definite cutting relation.

3. In a hand feeding embroidery edge trimming machine, the combination with a 80 rotary cutter operable about a horizontal axis, of a horizontally disposed work supporting device arranged in cooperative relation to said cutter and having an uninterrupted work supporting surface, and a foot device 85 disposed above the work support, said devices being respectively located in spaced parallel horizontal planes to provide a horizontal guiding channel for the body fabric during the hand feeding thereof, one of said 90 devices being provided with an embroidery-engaging flange to limit the movement of the fabric towards the cutter, said foot extending forwardly beyond the embroidered edge 95 of the fabric.

4. In an embroidery edge trimming machine, the combination with a rotary cutter operable about a horizontal axis, a horizontally disposed work supporting device disposed in cooperative relation to said cutter and having an uninterrupted work supporting surface, a foot device disposed above the work support, said devices being respectively located in spaced parallel horizontal planes to provide a horizontal guiding channel for the body fabric during the feeding thereof, said devices being formed with notches for receiving the teeth of the cutter, one of said devices being provided with an embroidery-engaging flange to limit the 110 movement of the fabric towards the cutter, a spring normally urging the foot vertically in one direction, and an adjusting screw for positively shifting the foot in the opposite direction against the tension of said spring. 115

5. In an embroidery edge trimming machine, the combination with a frame, of a rotary cutter supported by said frame and operable about a horizontal axis, a horizontally disposed work supporting device arranged 120 in cooperative relation to said cutter and having an uninterrupted work supporting surface, a foot device disposed above the work support, said devices being respectively located in spaced parallel horizontal 125 planes to provide a horizontal guiding channel for the body fabric during the feeding thereof, said frame having a socket disposed

above the foot, a shank secured to the foot, and extending upwardly into the socket, said shank having a shoulder, a coil spring disposed around the shank between the lower end of the socket and the shoulder, and an adjusting screw threaded into the upper end of the socket and engageable with the upper end of the shank to force the foot down-

wardly against the tension of said spring.

In testimony whereof I affix my signature 10
in presence of two witnesses.
